JAMES P. PARTLOW, OF COLUMBIANA, AND HOY L. POWELL, OF CANFIELD, OHIO

DESIGN FOR A GAME TABLE

Application filed February 4, 1932. Serial No. 42,726. Term of patent 3½ years.

To all whom it may concern:

Be it known that we, JAMES P. PARTLOW and Hoy L. POWELL, citizens of the United States, residing at Columbiana and Canfield, respectively, in the counties of Columbiana and Mahoning, respectively, and State of Ohio, have invented a new, original, and ornamental Design for Game Table, of which the following is a specification, reference being had to the accompanying drawing, forming part thereof.

We claim:

The ornamental design for a game table, as shown.

JAMES P. PARTLOW.
HOY L. POWELL.
